UNITED STATES PATENT OFFICE.

EMIL SEVERIN, OF AURORA, INDIANA.

METALLIC ROOFING.

SPECIFICATION forming part of Letters Patent No. 276,085, dated April 17, 1883.

Application filed November 20, 1882. (No model.)

To all whom it may concern:

Be it known that I, EMIL SEVERIN, of Aurora, Dearborn county, Indiana, have invented a new and useful Improvement in Metallic 5 Slating, of which the following is a specification.

My invention is designed to enable the manufacture out of tinned iron (tin-plate) or other sheet metal a roof-covering that will answer 10 all the useful purposes of slating at much less expense.

In the accompanying drawings, Figure 1 represents a portion of a roof partly covered with my "metallic slating." Fig. 2 is a vertical section of the same in direction of the 15 water-shed. Fig. 3 represents an under side view of one of the "tiles" or "slates" detached.

A may represent a part of an ordinary roof 20 sheathing.

B are my metallic tiles or slates, preferably of square or approximately square form, two contiguous edges being bent under to form lips C, and the other two edges being bent upward, backward, and again forward into an S 25 form, making lips D, which have holes d for

the fastening-nails E. Before bending, the corners of the plate are trimmed to produce the oblique terminations F. It will be seen that each line of nail-holes is completely hidden and protected by the superimposed tier of "slating," so as to produce a completely water-proof covering and a finished and sightly appearance.

The plates may be painted or enameled in 35 different tints, in imitation of slates or tiles, so as to produce a very ornamental appearance.

For the upper and the lower tiers half-tiles are used, such as would be produced by separation at the dotted line in Fig. 3.

I claim as a new article of manufacture—

The metallic slate or tile B, having its corners trimmed, as at F, and its edges bent, as at C and D, with perforations d in the lips D, substantially as and for the purpose set forth. 45

In testimony of which invention I hereunto set my hand.

EMIL SEVERIN.
